UNITED STATES PATENT OFFICE.

LEVIN T. JONES, OF BALTIMORE, MARYLAND.

UMBRELLA DRIP-CUP.

SPECIFICATION forming part of Letters Patent No. 330,789, dated November 17, 1885.

Application filed June 8, 1885. Serial No. 167,937. (No model.)

To all whom it may concern:

Be it known that I, LEVIN T. JONES, a citizen of the United States, residing at Baltimore, in the State of Maryland, have invented 5 certain new and useful Improvements in Umbrella Drip-Cups, of which the following is a specification.

My invention relates to an improved drip-cup for umbrellas. The object is to provide 10 a metal drip-cup and ferrule for attachment to the end of the stick or handle of an umbrella.

In the accompanying drawings, which illustrate the invention, Figure 1 is a vertical 15 central section of the drip-cup and ferrule attached to the umbrella-stick. Fig. 2 is a top view of the drip-cup detached. Fig. 3 is a view of the stay. Fig. 4 is a side view of the top part of the drip-cup. Fig. 5 is a side 20 view of the lower part or drip-cup proper and ferrule.

The letter A designates a metal ferrule part, which is to fit tightly on the end of the stick 25 or handle B, and be rigidly fastened thereto, as usual. This ferrule may be termed a "cap-ferrule," as it has a closed end, a. The drip-cup C is also made of metal, and at its lower end, d, is permanently attached to or integral 30 with the said ferrule, and both drip-cup and ferrule are water-tight. Thus constructed the umbrella can be carried and handled as a cane, because the ferrule part of the cup is a perfect protection to the stick, and there can be no leak of the rain-water that may be in the 35 cup.

This combined drip-cup and ferrule may go directly on the end of the stick, or may go entirely over a ferrule already on the stick. The drip-cup in the present instance has a 40 top part, C', which is rounded inward or contracts, as at e, toward the rim or opening f, and serves to exclude dirt or trash of any character, besides rendering the cup more sightly. To have the metal cup with this feature, it is necessary to construct it of two 45 parts. These parts may consist of two equal portions united on a longitudinal or vertical line, or may consist, as shown in the drawings, of the cup part proper, C, (shown separately in Fig. 5,) and the top part, C', (shown in Fig. 4.) These two parts may be spun or

stamped up, and fit snugly together, as the cover fits an ordinary blacking-box, and said parts are soldered. When the end of the stick B is entered and fitted tightly into the 55 ferrule A, and set or fastened thereto, as usual, by a prick-punch or in any other suitable manner, the cup will then be properly attached and the umbrella ready for use. To give greater rigidity, however, to the cup, a 60 stay, H, is provided. (See Figs. 1, 2, and 3.) This stay has a central ring, i, which is to encircle the stick B, and prongs or arms K radiate from the ring. The ends of the prongs bear against the inside wall of the cup, as at 65 l, and, as will be readily understood, the device serves to stay the cup against lateral movements. The cloth or cover n of the umbrella and the collar o are adjacent to the central opening, f, of the cup.

When the umbrella is closed, as shown in Fig. 1, an annular opening is left between the umbrella and the cup-rim f for the entrance into the cup of the rain-water drip.

The inward-contracted top C' and the stay 75 H are both desirable features of my improvement, and enhance the usefulness and value of the device; but my invention is not limited to a drip-cup provided with them.

I am aware drip-cups have been made or 80 proposed heretofore for umbrellas; but my device, consisting of a metal cup and ferrule in one solid or integral piece, is an improved article.

It will be seen the cup and ferrule are attached to the umbrella by simply slipping the ferrule on the end of the stick or handle, as usual, and that so applied the cup will be water-tight, while the ferrule will protect the stick and enable the umbrella to be handled 90 as a cane.

The advantages and mode of operation of the drip-cup from what has been stated are apparent.

Having described my invention, I claim and 95 desire to secure by Letters Patent—

1. An umbrella having in combination a drip-cup and ferrule, both water-tight and rigidly attached together, and a handle-stick, B, having its end entered in the said ferrule 100 and rigidly fastened thereto, as set forth.

2. A metal drip-cup for umbrellas, having

its lower end permanently attached to a metal cap-ferrule, and provided with a top part, which is rounded or contracted inward to a rim or opening, as set forth.

5 3. A metal drip-cup, C, for umbrellas, having its lower end permanently attached to a metal cap-ferrule, A, and a stay to prevent lateral movement and provided with a top part,

which is rounded or contracted inward to a rim or opening, as set forth.

In testimony whereof I affix my signature in presence of two witnesses.

LEVIN T. JONES.
